UNITED STATES PATENT OFFICE.

EDWARD DOLLAR, OF PIETERSBURG, TRANSVAAL, SOUTH AFRICA.

OPERATING MEANS FOR STAMP-MILLS.

1,082,015.

Specification of Letters Patent. Patented Dec. 23, 1913.

Application filed December 26, 1911. Serial No. 667,920.

To all whom it may concern:

Be it known that I, EDWARD DOLLAR, a subject of the King of Great Britain, and resident of Pietersburg, Province of Transvaal, Union of South Africa, have invented certain new and useful Improvements in Operating Means for Stamp-Mills, of which the following is a specification.

This invention relates to a means or device applicable for lifting and supporting, and thereby throwing out of action the stamps of stamp mills.

The use of most of the existing stamp supporting devices is attended with considerable risk and more or less serious accidents are of frequent occurrence.

Now the object of my invention is to provide a means or device which will be free from said objections.

20 I will now describe my invention in detail with the aid of the accompanying drawing in which—

Figure 1 is a view of one of the stamps operating in a mortar box showing the device in operative position or in the position in which the parts are placed to maintain the tappet clear of the cam. Fig. 2 is a front elevation of that form of the device shown in Fig. 1. Fig. 3 is an elevation at right angles to Fig. 2. Fig. 4 is a longitudinal section at right angles to Fig. 2. Fig. 5 is a front elevation of a slightly modified form of the invention. Fig. 6 is an elevation at right angles to Fig. 5. Fig. 7 is a side elevation illustrating a further modification, and Fig. 8 is an elevation at right angles to Fig. 7.

In Fig. 1, 1 represents the mortar box, 2 the stem of one of the stamps operating therein, 3, 4 upper and lower stem guides, 5, 6 the guide girths, and 7 one of the king posts. 8 is the cam shaft, 8^a the cam shaft bearing, 9 one of the cams fixed on the cam shaft 8, and 10 the tappet on the stem 2. 11 is the jack shaft, 12 one of the chairs for supporting one end of the jack shaft 11 and fixed to the king post 7. 13 is one of the fingers (one is usually provided for each stamp), and 14 is the socket piece in which the lower end of the finger 13 is secured by bolt 15. The socket fits the jack shaft as shown and allows the finger 13 to be placed in its operative position beneath the tappet 10—see Fig. 1. 16 is the shoe secured upon the upper end of the finger 13 by means of bolts 17. The finger may also be provided

with a suitable handle for operating it by hand.

In the construction shown in Figs. 1 to 4 a transverse hole 18 is formed through the finger 13 and a hole 19 is formed longitudinally through the finger from the upper end to said transverse hole 18. A coincident hole 19^a is also provided in the shoe 16. 20, 21 are bosses secured at opposite sides of the finger 13. Holes are provided in the bosses 20, 21 and coinciding holes are provided in the fingers on each side of the slot 18. 22 designates a pin which is rotatably supported in the bosses 20, 21 and passes through the slot 18. On the pin inside the slot 18 is fixed a cam 23. 24 is a rod which is placed inside the hole 19. Rod 24 at one end rests upon the surface of the cam 23. The rotation of the cam causes the rod to project beyond the upper end of the finger as shown in Fig. 1 and so increases the effective length of the finger 13. 25 is a lever fixed upon one end of the pin 22 for rotating said pin and with it the cam 23.

80 The manner of using the device is evident from Fig. 1 of the drawings.

As shown the finger 13 is placed beneath the tappet 10 with the rod 24 in its lowermost position. The lever 25 is then moved to rotate cam 23 which forces the rod 24 upward and so lifts the stamp to a sufficient height to clear the tappet 10.

In the modification illustrated in Figs. 5 and 6 the upper end of the finger is bifurcated or constructed with a recess or open-ended slot 26. A hole 27 is formed in the upper end of the finger and holes coinciding therewith are formed in the sides of the shoe 16. In the hole 27, a pin 28 is rotatably supported. Upon the pin 28 the cam 29 is fixed. The lever 30 is fixed upon one end of the pin 28.

The operation is the same as that previously described in connection with Figs. 1 to 4 with the exception that in this case the cam 29 will directly engage the tappet 10.

In the further modification shown in Figs. 7 and 8 the cam 31 is constructed in one piece or attached directly to the end of the lever 32, and the cam and lever move about the pin 33. The upper portion of the finger requires to be cut away or recessed as indicated at 34 to provide for the movement of the cam and lever. The operation of this modification is self evident.

What I claim as my invention and desire to protect by Letters Patent is:—

1. A device of the character described and comprising in combination a support a finger movable on said support and having a transverse slot and a longitudinal hole extending from said slot to the upper end of the finger, a pin rotatably supported in said slot, a cam secured upon said pin, means fixed to said pin at the outside of the finger for rotating the pin to operate the cam, and a rod located in the longitudinal hole, and engaging the cam which rod is projected beyond the end of the finger when the cam is rotated by means of the lever, as set forth.
2. In combination a jack shaft having suitable bearings, a socket piece rotatably supported upon said jack shaft, a finger the lower end of which is secured within said socket piece, a shoe secured upon the upper end of the finger, the finger having a transverse slot and a longitudinal hole extending from said transverse slot to the upper end of the finger and the shoe having

a hole coinciding with said longitudinal hole, bosses fixed to the sides of the finger opposite the transverse slot, the aforesaid bosses having holes and the finger having coincident holes at the sides of the transverse slot, a pin revolvably supported in said bosses and extending through the transverse slot, a cam fixed on said pin inside said slot, means fixed upon one end of said pin at one side of said finger for rotating said pin and with it the cam a rod located in the longitudinal hole and at its lower end engaging the cam which rod is projected beyond the end of the finger and through the coincident hole in the shoe when the cam is rotated by means of the lever, as set forth.

In testimony whereof I have signed my name to this specification in the presence of two subscribing witnesses.

EDWARD DOLLAR.
